UNITED STATES PATENT OFFICE

2,166,219

EXPANSION JOINT FOR CONCRETE PAVEMENTS OR THE LIKE

Clifford Older, Wilmette, Ill.

Application June 18, 1934, Serial No. 731,042
Renewed May 6, 1939

10 Claims.

(Cl. 94—18)

The present invention relates to expansion joints for concrete pavements and the like, and is particularly concerned with an improved expansion joint which does not require a plastic or semi-plastic filling material.

In the expansion joints of the prior art, the cracks appearing between the sections of pavement are ordinarily filled with a plastic or semi-plastic material, such as asphalt or tar. When such joints close due to the expansion of the adjacent concrete sections, all, or nearly all, of the plastic material is forced out at the top of the joint, since it is prevented from being forced out below the concrete by the presence of the sub-grade material. The plastic material which is forced out at the top of the joint forms, at least temporarily, ridges of material across the pavement, which are struck by the wheels of the passing vehicles, causing an impact blow to fall upon the adjacent concrete slabs. This often causes the slabs to become broken, unless they are made strong enough, at additional expense, to resist this extra force.

Ultimately, the ridges of semi-plastic material may be flattened out by traffic, but in the meantime, the pavement may be seriously damaged. If the plastic filler is soft enough so that it will flatten out immediately under traffic, it will also flow sidewise due to the crown of the pavement and leave the center only partially filled and the surplus flows over the surface of the pavement, forming unsightly pools.

It is also desirable that an expansion joint should permit widening of the joint or crack from its initial position and rewiden from any predetermined position, in order to take care of expansion in the summer and contraction of the concrete pavement sections in the winter. When a joint is filled with such plastic material, it cannot fulfill these functions, because the material which is forced out by the closing of the expansion joint crack is flattened out, and the joint must be refilled with plastic every time it opens, which is a nightly occurrence, if the joint is to be kept free from sand and other material.

One of the objects of the present invention is the provision of an improved expansion joint, in which no plastic or compressible filler is required.

Another object is the provision of an improved expansion joint which is capable of permitting either expansion or contraction of the concrete sections, and permitting a substantial widening or closing of the crack or space between the sections without exposing any opening

into which soil or other foreign material may enter and interfere with future effective operation of the joint.

Another object is the provision of an improved expansion joint construction, by means of which each section of concrete is supported and reinforced by the adjacent sections so as to eliminate the undue strains which would otherwise be imposed upon the concrete sections at their edges.

Another object is the provision of an improved sliding construction for an expansion joint, which is adapted to automatically maintain itself in clean and operative condition by virtue of its own operation, and which positively precludes the entrance of any dirt or foreign material between the adjacent sections of concrete.

Another object is the provision of an improved expansion joint assembly which is adapted to maintain the adjacent concrete sections in horizontal alignment to eliminate any possibility of one section settling below the other, or producing any bump or irregularity in the pavement of the joint.

Another object is the provision of an improved expansion joint assembly which may be manufactured out of standard structural shapes and plates, or which lends itself readily to manufacture out of sheet metal, so that the metallic members may be manufactured at a low cost.

Another object is the provision of an improved expansion joint assembly which may be installed as a unit in the concrete and supported without the aid of header boards, and which may also be used to end a day's run of concrete, thus entirely eliminating the boards usually employed for that purpose.

Another object is the provision of an improved method of constructing expansion joints by means of which a good bond is assured between the parts of the expansion joint and the concrete section, and the shrinking away of the concrete section from the expansion joint during the drying of the concrete is eliminated.

Another object of the invention is the provision of an improved expansion joint of the sliding type for concrete pavements in which the sliding parts are held in close contact with each other to eliminate any possibility of movement of one section of the concrete in a vertical direction with respect to the next adjacent section and, thus, to assure the transmission of the load from each section to each adjacent section.

Another object of the invention is the provi-

sion of an improved expansion joint of the class described in which less metal is required for the construction of the joint and less welding or other labor than the devices of the prior art.

5 Other objects and advantages of my invention will appear more fully from the following description and from the accompanying drawings, in which similar characters of reference indicate similar parts throughout the several views.

10 Referring to the drawings,

Fig. 1 is a fragmentary, transverse sectional view through two sections of concrete equipped with an expansion joint constructed according to the present invention, the section being taken 15 longitudinally of the road;

15 Fig. 2 is a similar view of a modification which is equipped with a sheet metal member forming a socket for the sliding flange at the bottom of the expansion joint;

20 Fig. 3 is a vertical elevational view of the expansion joint unit showing the adaptation of the unit to the contour and thickness of the road;

25 Fig. 4 is a view similar to Fig. 1 of another modification equipped with resilient means for holding the sliding elements of the joint in close contact with each other; and

30 Fig. 5 is a vertical elevational view of the expansion joint shown in Fig. 4, looking in the direction indicated at 5-5 in Fig. 4.

35 Referring to Fig. 1, 10 indicates a section of concrete pavement, or the like, immediately adjacent another section 11, the sections being equipped with an expansion joint indicated in its entirety by the numeral 12. The expansion joint 40 unit 12 is preferably so constructed that it may be handled as a unit having all of its parts secured together. Referring to Fig. 1, the joint of this embodiment is preferably formed with a pair of angle iron members 13, 14, each angle iron member having a horizontal flange, 15, 16 and a vertical flange 17, 18.

45 Integral lugs may be struck out of the vertical flanges 17, 18 and suitably formed to provide the anchoring formations, for example, the lugs 19 and 20 taper from their outer ends toward the flanges 17, 18, and the lugs being larger at their outer ends they are adapted to be firmly anchored in the concrete section 10.

50 The vertical flanges 17 and 18 of the angle iron members 13 and 14 are preferably joined by a relatively light sheet metal plate 21 which may be spot-welded to the flanges 17 and 18, as indicated on the drawings, and the plate 21 is preferably wide enough to cover the apertures formed 55 by striking out the lugs 19 and 20.

55 All of the parts of the joints described herein may be made of non-corrodible metal, such as stainless steel or steel plated with chromium, but parts which are not essential to the permanent 60 operation of the joint may be made of any metal adapted to perform the function required of it in the installation of the joint.

65 The horizontal flanges 15 and 16 are spaced sufficiently to locate them flush with the upper and lower surface of the concrete, by means of the plate 21, and they are adapted to slidably engage metallic parts upon the adjacent section 11 of concrete. The section 11 is provided at its upper edge with a sheet metal member having a horizontal flange 22, a downwardly extending flange 70 23 and an inwardly turned edge 24. The horizontal flange 22 may likewise have a plurality of anchoring members 25 struck out of the flange and turned downward to be embedded in the concrete section 11. In this case the anchoring

75 lugs 25 are provided with inwardly extending grooves 26 into which the concrete flows, thereby anchoring the lugs 25 firmly in the section 11. In order to hold the sheet metal 22 in proper position, it is provided with a plurality of apertures 27 which register with apertures 28 in the flange 15 of the angle iron 13, and flanges 15 and 22 are secured together by a plurality of screw bolts 29. Thus, the upper surface of flange 22 and the lower surface of flange 15 are held in close contact with each other during the installation of the joint in the concrete. The nut of the bolt 29 is embedded in the concrete section 11 and when the concrete has become sufficiently firm, the bolt 29 may be removed by means of a wrench or other tool, the nut remaining embedded in the concrete. It is, of course, necessary to remove the bolt 29 to permit the sliding action of the expansion joint.

80 The angle iron members 13 and 14 are preferably constructed out of ordinary stock angle irons in order to reduce the cost of the joint as much as possible, but the sheet metal member 22 may be made of lighter material. The inwardly extending edge 24 is adapted to provide an additional bearing surface for the sheet metal member 22 on the section 11 in case the concrete does not happen to flow up under the flange 22 at all points.

85 The expansion joint is preferably so constructed that there will be formed an open space 30 between the sections 10 and 11 of concrete and this may be accomplished by means of a light sheet metal plate 31 of sufficient width to fit between the flanges 15 and 16 and of sufficient length to extend the full length of the expansion joint. The plate 31 may be supported in place by providing it with a laterally and downwardly extending flange 32 and a laterally and upwardly extending flange 33 which also determines the spacing between the plate 31 and plate 21. The flanges 32 and 33 40 have sufficient angle so that when the sections of concrete 10 and 11 later expand, the flanges 32 and 33 will fold up against the body of the plate 31. The present joint is thus adapted to permit initial expansion or initial contraction of 45 the concrete.

90 At its lower edge the section 11 is also preferably provided with a sheet metal member 34 which may be made of relatively light stock having a flat body and an upwardly extending flange 35. At its opposite edge the body is turned diagonally downward at 36, thus forming the open space 37 below the concrete section 11 at its edge for the reception of the flange 16 of angle iron 14. In order to permit the unit handling of this 95 expansion joint, the flange 35 may be spot-welded to the body of the plate 31. When the joint is installed in the concrete, the plate 34 provides a smooth, sliding surface engaging the flange 16 of the angle iron 14 and any load on the section 11 is transmitted to the section 10 through the plate 34 and flange 16. Any load on the section 10 is transmitted to the section 11 by means of the angle iron flange 15 bearing on the plate 22 and thus, the two sections of concrete are constantly kept in alignment with each other. The lower flange 16 may be provided with a sharp forward edge 38, if desired, which is adapted to scale off any small amount of concrete which might penetrate into the space 37 below plate 34.

100 The shape of the complete expansion joint corresponds to the contour and thickness of the roadway, as shown in Fig. 3, the thickness of the concrete usually being increased at the edge of the road.

Referring now to Fig. 2, this is a modification in which all of the elements of the expansion joint may be just the same as that described with respect to Fig. 1, except that the lower flange 16 of angle iron 14 is provided with a sheet metal member 39 forming a socket for this flange in the concrete section 11. The sheet metal member 39 has a lower flange 40 and is bent back upon itself at 41, its upper flange 42 being spaced from the flange 40 sufficiently to receive the flange 16 on the angle iron member 14. Upper flange 42 has an upwardly extending flange 43 for engaging the division plate 31.

In order to secure the angle iron member 17 and the sheet metal member 39 in predetermined positions with respect to each other, the flange 16 is preferably provided with a plurality of apertures 44 and the flanges 40, 42 preferably have punched deformations 45 which extend down into 20 and up into the apertures 44 to hold these two members together.

The operation of this joint is the same as that of Fig. 1, the flanges 32, 33 of the division plate 31 crumbling up upon the further expansion of the concrete into the space 30. The punched deformations 45 are sufficient to hold these parts in the position shown in Fig. 2 during the installation of the joint, but they are not strong enough to prevent sliding between the flanges 16 and 40, 42. 30 When the concrete sections later expand or contract these deformations 45 soon become flattened out and do not interfere with the sliding movements of the elements of the expansion joint.

Referring now to Fig. 4, this is another modification adapted to be used where it is desirable to have a heavier metal plate on the lower part of the concrete section 11. In this embodiment corresponding parts of the expansion joint unit may be of similar construction to the top and left half 40 of the joint of Fig. 1. The lower right-hand part of the expansion joint is provided with a sheet metal member 46 similar in shape to the sheet metal member 22, except for the provision of the diagonally downward extending flange 54 similar 45 in structure and purpose to the flange 36 in Fig. 1 previously described, which is provided at the lower right. The flanges 46 and 16 are provided with apertures 47, 48 and the latter aperture is preferably screw-threaded to receive the threaded 50 end of an elongated screw bolt 49 which passes through the apertures 27, 28 and 47 and is threaded home in the threaded bore 48.

In order to maintain the sheet metal members 22 and 46 in the position of Fig. 4 and in close 55 contact with the flanges 15 and 16, a plurality of resilient spacing members 50 may be used, preferably located at each of the bolts 49. Each of the spacing members 50 may consist of an angle iron member having one flange 51 which is shorter 60 than the space between the flanges 22 and 46 and the other flange 52 which is longer than the space mentioned and bent laterally at its end 53. The end flange 53 is bent so as to make the spacer 50 initially longer than the space into which it is 65 forced between the flanges 22, 46 so that the end flange 53 is bent over from the position shown at the right of Fig. 5 to the position shown at the left of Fig. 5. The flanges 50 thus resiliently engage the flanges 22, 46 and hold them tightly 70 against flanges 15 and 16 during the handling and installation of the joint and after the concrete has hardened the bolts 49 may be removed so as to permit sliding between the two adjacent sections of concrete. The subsequent operation 75 of this joint is substantially the same as the joints

previously described. It will thus be observed that I have invented an improved construction of sliding expansion joint provided with spacing members having a residual spring after they are driven home between the parts of the expansion joint so as to insure tight contact of the top and bottom bearing plates with the main angle irons. This improved construction permits no lost motion or play in a vertical direction between the sliding parts of the bearing plates because these 10 parts are held tightly together by means of removable bolts and/or spacing members until the concrete has become firm enough to hold the parts in this position. Less metal and less welding is required in the manufacture of these expansion 15 joint units than is required in the devices of the prior art and the joint may, therefore, be constructed more cheaply.

While I have illustrated and described a preferred embodiment of my invention, many modifications may be made without departing from the spirit of the invention and I do not wish to be limited to the precise details set forth but desire to avail myself of all changes within the scope of the appended claims.

Having thus described my invention, what I claim as new and desire to secure by Letters Patent of the United States is:

1. In an expansion joint unit, the combination of a pair of angle irons each having a horizontally extending flange and a vertically extending flange, said vertically extending flanges being disposed towards each other and having a plurality of anchoring lugs struck out from said vertically extending flanges, means for fixedly securing said vertically extending flanges to each other in spaced relation to each other and in substantial alignment with each other, a pair of metal fittings adapted to be secured to an adjacent section of concrete, means for securing said latter 40 metal fittings in close contact with the inner surfaces of the horizontal flanges of said angle irons, and a division plate adapted to be located and temporarily secured in spaced relation to said vertical flanges to form an open space between 45 the ends of two adjacent sections of concrete to permit initial expansion of the concrete sections, said division plate comprising a relatively light sheet metal member extending from the horizontal flange of one angle iron to the horizontal 50 flange of the other angle iron and having transversely extending parts adapted to initially space the division plate from the vertical flanges of the angle irons.

2. In an expansion joint unit, the combination of a pair of angle irons each having a horizontally extending flange and a vertically extending flange, said vertically extending flanges being disposed towards each other and having a plurality of anchoring lugs struck out from 55 said vertically extending flanges, means for fixedly securing said vertically extending flanges to each other in spaced relation to each other and in substantial alignment with each other, a pair of metal fittings adapted to be secured to an adjacent section of concrete, means for securing said latter metal fittings in close contact 60 with the inner surfaces of the horizontal flanges of said angle irons, and a division plate adapted to be located and temporarily secured in spaced 65 relation to said vertical flanges to form an open space between the ends of two adjacent sections of concrete to permit initial expansion of the concrete sections, said division plate comprising a relatively light sheet metal member extending 70

75

- from the horizontal flange of one angle iron to the horizontal flange of the other angle iron and having transversely extending parts adapted to initially space the division plate from the 5 vertical flanges of the angle irons, said transversely extending parts comprising diagonally downward and upward extending flanges at the top and bottom of said division plate adapted to be bent when the concrete sections expand.
- 10 3. In an expansion joint unit, the combination of a pair of angle irons each having a horizontally extending flange and a vertically extending flange, said vertically extending flanges being disposed towards each other and having 15 a plurality of anchoring lugs struck out from said vertically extending flanges, a sheet metal member having a horizontally extending flange and a vertically extending flange adapted to be secured to the adjacent upper corner of a concrete section and a similar sheet metal member adapted to be secured to the adjacent lower corner of an adjacent concrete section, said lower sheet metal member having a downwardly extending flange at its inner edge engaging said 20 concrete section to form a recess below the adjacent edge of said adjacent concrete section for receiving the lower horizontal flange of said angle iron, and removable means for securing said sheet metal members with their horizontal 25 flanges in close engagement with the horizontal flanges of said angle irons.
4. In an expansion joint unit, the combination of a pair of angle irons each having a horizontally extending flange and a vertically extending flange, said vertically extending flanges being disposed towards each other and having a plurality of anchoring lugs struck out from 30 said vertically extending flanges, a sheet metal member having a horizontally extending flange and a vertically extending flange adapted to be secured to the adjacent upper corner of a concrete section and a similar sheet metal member adapted to be secured to the adjacent lower corner of an adjacent concrete section, said lower 35 sheet metal member having a downwardly extending flange at its inner edge engaging said concrete section to form a recess below the adjacent edge of said adjacent concrete section for receiving the lower horizontal flange of said angle iron, and removable means for securing said sheet metal members with their horizontal 40 flanges in close engagement with the horizontal flanges of said angle irons.
- 45 5. In an expansion joint unit, the combination of a pair of angle irons each having a horizontally extending flange and a vertically extending flange, said vertically extending flanges being disposed towards each other and having a plurality of anchoring lugs struck out from said vertically extending flanges, a sheet metal member having a horizontally extending flange and a vertically extending flange adapted to be secured to the adjacent upper corner of a concrete section and a similar sheet metal member adapted to be secured to the adjacent lower corner of an adjacent concrete section, said lower sheet metal member having a downwardly extending flange at its inner edge engaging said concrete section to form a recess below the adjacent edge of said adjacent concrete section.

for receiving the lower horizontal flange of said angle iron, and removable means for securing said sheet metal members with their horizontal flanges in close engagement with the horizontal flanges of said angle irons, comprising a threaded member having a non-circular head and extending through the horizontal flanges of said angle irons and said metal members, said threaded member engaging a threaded bore in the horizontal flange of said lower angle iron, and resilient spacing members located between the horizontal flanges of said metal members and holding said latter horizontal flanges tightly against the horizontal flanges of said angle irons.

6. In a concrete expansion joint unit, the combination of four metal members each having horizontally extending flanges and each having anchoring lugs adapted to be embedded in an adjacent section of concrete, means for temporarily securing said horizontal flanges to each other in position to permit sliding movement of said horizontal flanges in either of two directions relative to each other, and means engaging the innermost of said horizontal flanges and urging said latter innermost horizontal flanges into close contact with the outermost of said horizontal flanges.

7. In a concrete expansion joint unit, the combination of four metal members each having horizontally extending flanges and each having anchoring lugs adapted to be embedded in an adjacent section of concrete, means for temporarily securing said horizontal flanges to each other in position to permit sliding movement of said horizontal flanges in either of two directions relative to each other, and resilient means engaging the innermost of said horizontal flanges and urging said latter innermost horizontal flanges into close contact with the outermost of said horizontal flanges, said resilient means comprising a plurality of relatively stiff metal members provided with resilient diagonally extending portions at one end and adapted to be driven home between said innermost horizontal flanges.

8. In an expansion joint for concrete pavements or the like, the combination of a pair of stock angle iron members each having a horizontally extending flange and a vertically extending flange, said vertically extending flanges having laterally projecting anchoring lugs struck from said vertically extending flanges, means for securing said vertically extending flanges in spaced relation to each other, comprising a metal plate welded to said vertically extending flanges, a metal fitting having a horizontally extending flange and having anchoring lugs struck downward out of said horizontally extending flange, said fitting being temporarily bolted to the upper of said horizontally extending flanges and a sheet metal member formed with a hairpin bend and having parallel flanges engaging on both sides of the lower of said horizontally extending flanges on said angle iron members, said sheet metal member forming a socket in an adjacent section of concrete for the sliding reception of the lower horizontal flange of said angle iron members, the horizontal flange of said lower angle iron having a plurality of sockets formed therein, and punched deformations on said sheet metal member holding said sheet metal member with said horizontal flange in such sheet metal member in predetermined position, and a division plate having a flat body in spaced relation to the plate connecting said angle irons, said division plate having spacing flanges adapted to be bent when the concrete expands.

9. In an expansion joint unit for concrete pavement or the like, the combination of metal members for the top and for the bottom of two adjacent sections of concrete, said metal members having horizontal flanges adapted to be secured to each section at the top and other horizontal members to be secured to each section at the bottom, and spaced metal plates forming end plates during the pouring of the concrete, said spaced metal plates being adapted to provide a space between the adjacent sections of concrete to permit initial expansion of the concrete, and means carried by one of said plates for temporarily holding said plates in spaced relation but adapted to be bent upon expansion of the concrete.
10. In a joint for concrete structures, the combination of a pair of adjacent sections of concrete, said sections having a crack formed between them at their juncture, with a load transmitting member having a flange extending in the general direction of the crack between the sections and lo-

cated substantially at said crack, said load transmitting member having integral anchoring lugs formed out of said flange and having a load transmitting flange extending substantially parallel to a surface on the opposite concrete section, said latter flange being located in sliding engagement with said surface on the opposite concrete section, and the anchoring lugs extending oppositely from said first flange and being fixedly embedded in the other concrete section, whereby loads on the one concrete section are transmitted through the said flange and load transmitting member to the other concrete section, to maintain alignment of said sections, and a shield for said horizontal flange comprising a sheet metal member having anchoring formations embedded in the other section of concrete and having a downwardly turned edge engaging the sub-grade to prevent concrete from entering under the shield and to provide a space for said horizontal flange.

CLIFFORD OLDER.
